UNITED STATES PATENT OFFICE

HARLEY A. W. HOWCOTT, OF NEW ORLEANS, LOUISIANA

SECTIONAL BARREL FOR FLUIDS

Application filed January 14, 1929. Serial No. 332,535.

My invention relates to sectional barrels, and especially those used in shipment of fluids, and it consists in the combinations, constructions and arrangements herein described and claimed.

An object of my invention is to provide a barrel having two separate compartments whereby a shipper may readily transport two separate fluids within a single container.

10 A further object of the invention is to provide a sectional barrel wherein the sections are readily assembled to form a complete barrel unit, or, if desired, but one section may be employed for shipment of a smaller quantity 15 of liquid.

A still further object of the invention is to provide a barrel in which the sections are securely held together by simple fastening means.

20 It is a still further object of the invention to provide a partition plate which will effectively seal the sections against leakage.

A still further object of the invention, is the provision of a barrel which may be readily 25 dismantled, the parts being constructed so as to be readily nested thereby occupying a minimum amount of space.

Other objects and advantages will appear in the following specification and the novel 30 features of the invention will be particularly pointed out in the appended claims.

My invention is illustrated in the accompanying drawings forming a part of this application, in which,

35 Figure 1 is a longitudinal sectional view of my barrel, showing the parts in assembled relation,

Fig. 2 is a cross section on the line 2—2 of Fig. 1,

40 Fig. 3 is a longitudinal section illustrating the manner of nesting the sections,

Fig. 4 is a perspective view of an assembled barrel and wrench for manipulating the fastening members,

45 Fig. 5 is a detail perspective view of the container as assembled for shipment of a smaller amount of liquid.

In carrying out my invention I provide substantially cup-shaped sections 1 and 2, in the 50 present instance, these sections forming the

contour of an ordinary barrel when assembled. The head 3 of the sections 1 and 2 is provided with an inwardly depressed recess 4, for a purpose which will be explained. Suitable bungs 5 are provided in the sections 55 1 and 2.

As clearly shown in Figures 1 and 4 the sections 1 and 2 are adapted to have their open ends presented within an annular recess 6 of a partition head 7. A rubber gasket 8 is provided within the recess 6, the gasket being U-shaped in cross section and adapted to receive the open end of the barrel sections there-within to effect a liquid-tight seal.

The head 7 is provided with a central boss 65 9, in which there are threadedly engaged the rods 10. The tie rods 10 are disposed upon opposite sides of the head 7 and extend into close proximity of the heads 3.

Reference is now made to Fig. 1, wherein 70 it will be seen that the tie rods 10 are provided with an enlargement 11 adapted to receive a gasket 12. A threaded bore 13 is formed in the tie rods 10 extending through the enlargement 11, and into the rod 10 a 75 sufficient distance, for reception of a bolt 14.

In assembling my barrel, the section 2 is set in an upright position disposing the open end upwardly, and upon this open end I position the partition head 7 with its associated 80 tie rods thereover, so that one of the recesses 6 circumscribes the open end. With the parts in this position, the tie rod will be centered with respect to the aperture 15 of the recess 4, the gasket 12 being interposed between the 85 enlargement 11 and the recess 4. The parts are secured in this relation by the bolt 14, as will be apparent. The remaining section 1 is next placed within the oppositely disposed recess 6 of the partition, and secured 90 as in the first instance.

It will be readily apparent, that by tightening the bolt 14, the gaskets 8 and 12 will be compressed between the abutting surfaces, and thereby effect a liquid-tight seal.

95 In Fig. 5, I have illustrated my invention as embodied when shipping a smaller quantity of fluid. In this instance, the construction of the container is identical with that previously described, and the only variation 100

is that but a single cup member 2 is employed, and the upper tie rod 10 and fastening means have been removed from the partition 7.

When it is desired to dismantle a barrel for nesting of the parts, it is only necessary to remove the bolts 14, with a wrench, such as illustrated at 16, which will permit removal of the cup-shaped members 1 and 2 from the partition 7. The tie rods 10 are next unscrewed from the partition 7. The tie rods and gasket 12 may be placed within their respective cup members and the cup members nested one within the other, as clearly shown in Figure 3. The partition 7 is positioned over the open end of the uppermost container, thereby closing the container and preventing loss of the parts therewithin.

The cup members 1 and 2 and partition 7 are provided with a plurality of notches 17, (see Fig. 4), in which a binding cord or cable 18 may be arranged to hold the several parts in their nested relations.

From the foregoing, it will be seen that I have provided a container which will permit ready shipment of two different fluids within a single container without liability of contaminating one another; and that I have also provided a container which may be readily dismantled so that the various parts may be nested in such manner as to occupy a minimum amount of space for storage or otherwise.

What is claimed is:—

1. A barrel comprising a pair of sections, a partition therebetween, and tie means extending from and fastened to the opposite sides of said partition and to the opposing ends of said sections.

2. A barrel comprising a pair of sections, said sections having an open and closed end, a partition disposed between the open ends of said sections and tie rods connects to and extending between said partition and said closed ends.

45 3. A barrel comprising a pair of substantially cup-shaped sections, a partition therebetween, said partition having oppositely disposed annular recesses for engagement around said cup-shaped sections, tie rods carried by said partition, said tie rods snugly abutting said cup-shaped members, and means carried by said cup-shaped members to secure said cup-shaped members to said rods.

55 4. A barrel comprising a pair of cup-shaped members, a partition therebetween, said partition having oppositely disposed recesses, a flexible gasket therein, said cup-shaped members being in abutting relation with said gasket, tie rods carried by said partition and extended into close proximity to said cup-shaped members, a flexible gasket carried by said tie rods, and means operable 65 exteriorly of said cup-shaped members for

compressing said gaskets and retention of said cup-shaped members within said recesses.

6. A container comprising in combination a pair of cup-shaped sections, a partition therebetween, tie rods carried by and fixed to said partition and abutting the closed ends of said sections, and means operable exteriorly of said cup-shaped sections to engage said tie rods to hold the parts in snug fluid tight relationship.

7. A container comprising in combination a pair of cup-shaped sections, a partition therebetween, and tie means fixed to said partition and said sections and extending interiorly of said sections.

8. A barrel comprising a pair of sections, a partition therebetween, tie members connected to and extending from said partition and abutting the closed ends of said sections and additional tie members engageable with said sections, said tie members and said additional tie members being adapted for releasable interconnection.
